UNITED STATES PATENT OFFICE.

CHARLES H. DRIVER, OF RACINE, WISCONSIN, ASSIGNOR TO J. MOORES JONES, OF RACINE, WISCONSIN.

BLADE-ATTACHING DEVICE FOR METALLIC CUTTING-MACHINES.

1,281,148.

Specification of Letters Patent.

Patented Oct. 8, 1918.

Application filed November 15, 1917. Serial No. 202,173.

To all whom it may concern:

Be it known that I, CHARLES H. DRIVER, a citizen of the United States, and resident of Racine, in the county of Racine and 5 State of Wisconsin, have invented certain new and useful Improvements in Blade-Attaching Devices for Metallic Cutting-Machines; and I do hereby declare that the following is a full, clear, and exact description 10 thereof.

My invention relates to certain new and useful improvements in metallic cutting machines and refers more particularly to that type known as power hack saws.

15 The present manner of securing a hack saw blade in its frame by providing its ends with apertures engaging a pin or stud carried by the blade attaching members is faulty, in that the blade is not held true in 20 its frame, and my invention has for its primary object to provide novel means for rigidly securing the blade in its frame so that each end thereof will be firmly held flush against its attaching bar or member 25 and thus retained in the frame.

With the above and other objects in view which will appear as the description proceeds, my invention resides in the novel construction, combination and arrangement of 30 parts substantially as hereinafter described and more particularly defined by the appended claims, it being understood that such changes in the precise embodiment of the herein disclosed invention may be made as 35 come within the scope of the claims.

In the accompanying drawings I have 40 illustrated one complete example of the physical embodiment of my invention constructed according to the best mode I have so far devised for the practical application of the principles thereof, in which:

Figure 1 is a side elevational view of a portion of the outer end of a power hack saw frame equipped with my device.

45 Fig. 2 is a longitudinal sectional view through the inner end of the blade attaching bar taken on the line 2—2 of Fig. 1.

Fig. 3 is a transverse sectional view 50 through one end of the hack saw blade looking at the inner end of the blade attaching bar and being taken on the line 3—3 of Fig. 1, and

Fig. 4 is a view, partly in section and

partly in elevation, taken on line 4—4 of Fig. 2.

55

Referring now more particularly to the accompanying drawings the numeral 1 designates one of the vertical legs or members of a hack saw blade retaining frame, as in this instance the outer leg member, in 60 the end of which is slidably mounted a blade attaching bar or member 2 having its inner end provided with novel means for engaging one end of the hack saw blade 3 and its outer end provided with a series of studs or projections 4 adapted to be engaged by the lower end of a fulcrum lever 5 having its upper end engaged by a tensioning screw or nut 6, all of which are of well known construction and constitutes no part of the present invention.

65

As will be readily understood, my invention is also applied to the stationary blade attaching member carried by the rear leg of the hack saw frame (not shown), but for the purpose of illustration the same has been depicted in the drawings as secured to the adjustable blade attaching bar or member 2 and resides essentially in providing the inner end of the attaching bar with an inwardly tapered portion 7 forming a consequent shoulder 8 at its termination and slidably mounted on the tapered portion is a 70 yoke 9.

75

Said yoke is substantially U-shaped and 80 straddles the bar 2, the ends of its arms having a plate 11 secured thereto by rivets or the like 12. The inner face with the plate is inclined as at 10 for coacting engagement with the tapered portion of the bar 2, whereby when stress is applied to the latter, its flat face will move toward the similar face of the base of the yoke. The plate 11 has an aperture 13 registering with an aperture 13' in the base of the yoke 9 and a slot 13" in 85 the bar 2 and, through said apertures and slot, a pin 14 is passed to engage the aperture 3' of the blade 3. The blade 3 is secured between the inner face of the base and the inner flat face or rear wall of the attaching bar 2 and the end of said pin 14 engages the aperture 3' provided in each end of the hack saw blade, the yoke and inner end of the attaching bar 2 being recessed as 90 at 15 to provide space for the pitch of the 100 hack saw blade, as best shown in Fig. 3.

95

100

105

As will be apparent from Fig. 2, when the blade is to be inserted in the hack saw frame, the pin 14 is drawn from engagement with aperture 13' by means of its knob 14', a bead 5 or flange 16 limiting the outer movement thereof and seating in a recess 16' provided in the plate 11 and concentric with aperture 13 to permit the movement of the yoke 9 toward shoulder 8, when the blade is inserted 10 therebetween as before stated. After the blade has been inserted between yoke 9 and bar 2, the pin 14 is again moved to engage the aperture in the hack saw blade and aperture 13', and upon the tensioning of the 15 binding screw 6 the fulcrum lever 5 will draw bar 2 outwardly, causing the cam faces of the yoke 9 and bar 2 to co-act to firmly bind the blade flush against bar 2 and thus securely retain the same true in the hack 20 saw frame, as will be obvious.

As before stated, any form of tensioning means may be employed in place of the fulcrum lever 5 and binding screw 6 and the inner stationary blade attaching bar or member (not shown), is equipped with the device hereinbefore described.

I claim:

1. A device of the character described comprising an attaching member, a yoke member carried thereby, said yoke member having apertures therein alining with a slot in one end of said attaching member, a pin 30 engaging the said apertures for retaining the end of a hack saw blade between the yoke member and said attaching member, and means independent of said pin for rig- 35

idly binding the end of said blade between said yoke member and attaching member.

2. A device of the character described comprising an attaching bar, a substantially **U**-shaped yoke member slidably straddling said bar, a pin extending through said yoke member and bar to attach a saw blade thereto, and means independent of the pin and carried by the yoke member for coöperative 40 engagement with the attaching bar to rigidly bind the end of the blade between the yoke member and the attaching bar when stress is applied to the last mentioned parts.

3. A device of the character described comprising an attaching bar provided on one side adjacent one end with an inclined face, the other side being flat, a substantially **U**-shaped yoke member slidably straddling said end of the bar, a plate secured between 55 the ends of the arms of the yoke member, the inner face of said plate being inclined for coöperative engagement with the inclined face of the attaching bar, said yoke member and plate having alined apertures, and a pin 60 extending through said apertures for retaining the end of a saw blade, said blade being rigidly clamped between the flat face of the bar and the inner face of the yoke member when stress is applied to the last mentioned 65 parts.

In testimony that I claim the foregoing I have hereunto set my hand at Milwaukee, in the county of Milwaukee and State of Wisconsin.

CHARLES H. DRIVER.
